UNITED STATES PATENT OFFICE

HARRY G. LUIS, OF SAN QUENTIN, CALIFORNIA, ASSIGNOR OF FORTY-NINE ONE-HUNDREDTHS TO CLYDE HENDRICKS, OF SAN QUENTIN, CALIFORNIA.

COMBINED MANDOLIN AND GUITAR.

1,241,639.

Specification of Letters Patent.

Patented Oct. 2, 1917.

Application filed April 7, 1917. Serial No. 160,495.

To all whom it may concern:

Be it known that I, HARRY G. LUIS, a citizen of the United States, residing at San Quentin, in the county of Marin and State of California, have invented certain new and useful Improvements in Combined Mandolins and Guitars, of which the following is a specification, reference being had to the accompanying drawings.

10 This invention relates to certain improvements in combined mandolin and guitar and it is an object of the invention to provide a device of this general character having novel and improved means whereby a singing tone 15 is created.

The invention consists in the details of construction and in the combination and arrangement of the several parts of my improved musical instrument whereby certain 20 important advantages are attained and the device is rendered simpler, less expensive and otherwise more convenient and advantageous for use, all as will be hereinafter more fully set forth.

25 The novel features of the invention will hereinafter be definitely claimed.

In order that my invention may be the better understood, I will now proceed to describe the same with reference to the accompanying drawings, wherein

Figure 1 is a view in top plan of a musical instrument constructed in accordance with an embodiment of my invention;

Fig. 2 is an enlarged sectional view taken 35 substantially on the line 2—2 of Fig. 1;

Fig. 4 is an enlarged sectional view taken substantially on the line 3—3 of Fig. 1;

Fig. 4 is an enlarged sectional view taken substantially on the line 4—4 of Fig. 1;

40 Fig. 5 is an enlarged sectional view taken substantially on the line 5—5 of Fig. 1;

Fig. 6 is an enlarged sectional view taken substantially on the line 6—6 of Fig. 1;

Fig. 7 is a fragmentary longitudinal sectional view taken substantially on the line 7—7 of Fig. 4;

Fig. 8 is a horizontal sectional view taken through the body of the instrument as herein disclosed with the back board in plan;

50 Fig. 9 is also a horizontal sectional view taken through the body with the face board in plan;

Fig. 10 is a view in elevation of the upper brace member carried by the face board;

55 Fig. 11 is a view in elevation of the upper brace member carried by the back board;

Fig. 12 is a view in elevation of the second brace member carried by the face board;

Fig. 13 is an enlarged sectional view taken substantially on the line 13—13 of Fig. 12; 60 and

Fig. 14 is a view in perspective of a musical instrument constructed in accordance with a further embodiment of my invention.

As disclosed in Figs. 1 to 7 of the accompanying drawings, B denotes the body of the instrument which may be of any suitable design but preferably of the configuration illustrated in Fig. 1, and in producing the body I find it of especial importance to 70 have the back board 1 of maple, the sides or bands 2 of eucalyptus and the face board 3 of white sugar pine with the grain transversely disposed. I have found by actual practice that white sugar pine results in an 75 unusually sweet tone. With a body constructed with the combination of woods just recited it has been fully demonstrated that a powerful sound may be created which, when close to the instrument, is soft but loud 80 at a distance.

The upper portion of the body B adjacent the opposite sides thereof is provided with the scrolls 4 which afford echo chambers to increase the sounds while the lower portion 85 of the body B adjacent one side is provided with the additional scroll 5 also affording an echo chamber.

At substantially its transverse center the body B has suitably secured to its upper end portion the neck 6 to the outer end portion of which is suitably secured the head 7 provided with a lateral extension 8 which serves as a sub-base head. The extension or head 8 is also suitably connected with the outer 90 end portion of the neck 9 suitably secured to the upper portion of the body B at one side of the neck 6. The body B has also secured to its upper end portion at the opposite side of the neck 6 the guitar neck 10 to the outer 100 end portion of which is secured the head 11. Interposed between the heads 7 and 11 is a bracing member 12 herein disclosed as comprising two threaded members having co-acting therewith a conventional type of turn 105 buckle. By the use of the brace member 12 it will be at once self-evident that relative movements of the heads 7, 8 and 11 are prevented.

In longitudinal alinement with each of the heads 8 and 11 the face board 3 of the body B has a sound outlet opening 14, in

longitudinal alinement with the head 7 is the sound outlet opening 14' positioned above the openings 14, the finger boards 15 of the necks 6 and 10 extend over the face board 3 and partially overlie the openings 14 and 14' alined therewith.

Suitably secured to the lower end portion of the body B is the double tail piece 16 with which are engaged the strings S coacting with the head 8 and the strings S¹ coacting with the head 11. The strings S and S¹ also overlie the bridges 17 suitably affixed to the outer face of the face board 3 and in close proximity to the double tail piece 16. At a point intermediate the strings S and S¹ and at substantially the center of the face board 3 is secured the combined tail piece and bridge 18. Operatively engaged with the combined tail piece and bridge 18 are the strings S² which are also operatively engaged with the head piece 7.

Secured to the under surface of the face board 3 adjacent the upper end of the body B is the brace member a extending entirely across the body B and also through the scroll 4 at the left side of the body as seen in Fig. 1, and said brace a is disposed on an incline relative to the longitudinal axis of the body. Also secured to the under surface of the face board 3 is a second brace member c extending from one side of the body adjacent the upper end thereof and terminating at the opposite side of the body adjacent the lower end thereof. A third brace e is secured to the under surface of the face board 3 which is positioned below the lower end of the brace c and is disposed at substantially right angles to the longitudinal axis of the body.

Secured to the back board 1 of the body adjacent the upper end thereof is the brace member b which extends entirely across the body B and is arranged in a plane intersecting the plane occupied by the brace member a. At substantially the longitudinal center of the body B the inner surface of the back board 1 has suitably secured thereto a second brace member d extending entirely across the body B and substantially at right angles to the longitudinal axis of the body B. The inner surface of the back board 1 has also secured thereto a third brace member f also extending entirely across the body B and arranged on an incline relative to the longitudinal axis of the body and positioned intermediate the brace members d and e. Secured to the inner surface of the back board 1 adjacent the lower end of the body B is a further brace member g which is disposed at right angles to the longitudinal axis of the body and occupies a plane intersecting the scroll 5. The inner surface of the back board 1 coacting with the scroll 5 is provided with the brace member h extending entirely across the scroll 5 and posi-

tioned in the same plane as the brace member g.

It is thought to be self-evident that the arrangement of the various brace members hereinbefore referred to affords a body possessing great strength.

In order to produce a "singing tone" I find it of advantage to employ the tube 19 provided at one end with the cup-like member 20 secured to the under surface of the face board 3 immediately beneath the combined tail piece and bridge 18, while the opposite end portion terminates in the funnel-like lateral extension 21 arranged immediately beneath the sound opening 14 in alignment with the tail piece and bridge 18.

As is particularly disclosed in Fig. 7, the tube 19 is disposed longitudinally of the body B. It has been fully demonstrated in practice that the tube 19 and its concomitant parts serve to form a tone chamber in which the tone is materially amplified so that the singing or after-tones will be so increased as to render the same readily audible.

In the form of my invention illustrated in Fig. 14, the body B¹ is constructed in substantially the same manner as has been set forth relative to the body B except I find it of importance to provide the lower end of the body B¹ at opposite sides thereof with the inwardly directed scrolls 5^a, whereby additional echo chambers are afforded. The structural parts disclosed in Fig. 14 which correspond to parts shown in the preceding figures are identified by corresponding reference characters.

In order to help maintain or hold the tone, certain of the various braces secured to the back board 1 and the face board 3 are provided with the lateral extensions 22 preferably positioned at the end portions of said braces.

I claim:

1. A combined mandolin and guitar comprising a hollow body having a scroll formed at the lower end thereof to provide an echo chamber, a plurality of necks extending from the opposite end of the body, strings on each neck, the body being provided with sound openings beneath the strings and a tube positioned beneath the sound opening of the central neck, and bridges for the strings mounted on the body, the central bridge being positioned over one end of the tube.

2. A combined mandolin and guitar comprising a hollow body having a scroll at its lower end to provide an echo chamber, a pair of scrolls at the upper end of the body, a plurality of necks extending upwardly from the body between the last named scrolls, a plurality of bridges mounted on the body, said body being provided with sound openings, strings con-

nected to the necks and the bridges and passing over the sound openings, and a tube attached beneath the central bridge and extending to a point in alinement with 5 the central sound opening.

3. A combined mandolin and guitar comprising a hollow body having a plurality of sound openings arranged in its 10 face, bridges attached to the body, necks extending from the end of the body opposite that to which the bridges are connected, a head connecting one pair of necks, a head on the opposite neck, a turn-buckle con-

necting the heads, strings on the necks and passing over the bridges, a tube secured beneath the centermost bridge and extending to a point immediately beneath the central opening and a horn at the end of the sound tube. 15

In testimony whereof I hereunto affix my 20 signature in the presence of two witnesses.

HARRY G. LUIS.
